UNITED STATES PATENT OFFICE.

ROBERT W. CHRISTIAN, OF BANNACK, MONTANA.

DREDGING-BUCKET.

SPECIFICATION forming part of Letters Patent No. 726,640, dated April 28, 1903.

Application filed November 23, 1901. Serial No. 83,455. (No model.)

To all whom it may concern:

Be it known that I, ROBERT W. CHRISTIAN, a citizen of the United States, residing at Bannack, in the county of Beaverhead and 5 State of Montana, have invented a new and useful Dredging-Bucket, of which the following is a specification.

This invention relates to bucket conveyers, and while particularly intended for dredging-machines it will be readily seen that the structure is capable of use in connection with conveyers of other kinds.

The width of the buckets of dredging-machines now in general use is limited, for the 15 reason that the pivotal connections between them are located at the sides, and the farther these connections are separated the weaker will be the conveyer. The connections are also subject to excessive wear, and the couplings as ordinarily constructed have to be frequently repaired or renewed. This wear is occasioned by the grit which works into the joints and grinds them out until said joints are loose, consequently throwing the buckets 20 out of alinement.

One of the objects of the present invention is to improve the construction of the buckets, and especially the connections between the same, so that they are much stronger and 30 will permit of wider buckets being employed, at the same time making the several elements entirely interchangeable, so that any one may be readily removed and replaced.

A further and important object is to provide a novel form of pivot-pin and means for locking the same in place, said pin and locking means being so constructed that they may be reversed to present new wearing-surfaces, thus prolonging the life and usefulness of 40 the pin. In connection with this a reversible bushing is also employed, which when worn may be turned to bring another surface into coacting relation with the pin.

In the accompanying drawings the preferred embodiment of the invention is fully 45 illustrated, and this embodiment is also described in the following specification.

It will of course be understood that the right is reserved to make such changes and 50 modifications from the construction set forth as the scope of the appended claims will permit.

In the drawings, Figure 1 is a side elevation of a portion of a conveyer constructed in accordance with the present invention. 55 Fig. 2 is a central vertical sectional view through the same. Fig. 3 is a sectional view taken on the line $x-x$ of Fig. 2. Fig. 4 is a detail view showing the means for locking the pivot-pin in place. Fig. 5 is a detail perspective view of the locking-pin, and Fig. 6 is a detail perspective view of the locking-plate.

Similar numerals of reference designate corresponding parts in all the figures of the 65 drawings.

The bucket as a whole is designated by the reference-numeral 10 and comprises a rear wall 11, to which is riveted the sheet-metal hood 12, having the usual lip 13. This hood 70 12 and lip 13 in themselves form no part of the present invention and may be changed or modified as desired. The rear wall 11 is preferably a casting, the lower portion of which is provided with eyes 14, the inner ends 75 of which are spaced apart to form a socket 15, the inner wall of said socket being inset, as shown at 16. The opposite end of the rear wall 11 is provided with a plurality of spaced eyes 17, the central one of which is located 80 in alinement with the socket 15 at the lower end, while the spaces between said eyes 17 form sockets 18 in alinement with the eyes 14 of the lower end. Similarly-constructed links 10^a connect the upper end of one bucket 85 with the lower end of the adjacent bucket, as will be readily understood. By referring to Fig. 3 it will be seen that the lower eyes 14^a of said links will fit in the upper sockets 18 of the adjacent bucket, while the central upper eye 17^a of the link will be located in the socket 15 and the two outer eyes 17^a will embrace the lower eyes 14. Channels 19 are located in the outer faces of the outer eyes 17, said channels intersecting the openings 95 through the eyes and preferably being equal in width to the diameter thereof. A pivot-pin 20 is passed through the several alined eyes, as shown in Fig. 3, and has a cross-head 21, that projects on opposite sides of the shank 100 and fits in one of the channels 19, whereby said pin is held against rotation, and said cross-head also constitutes holding means that is located in one of the channels to pre-

vent longitudinal displacement of the pin in one direction. The end of the pin opposite the head is provided with an annular groove 22, and this end having said groove projects 5 into the channel 19 of the other outer eye. A locking device in the form of a plate 23 is secured in this channel by means of a rivet 24 and has a bifurcated portion 25, which embraces the end of the pin and engages in the 10 groove 22 thereof, the locking-plate thus also constituting holding means located in the other channel to secure the pin against accidental displacement. The pin 20 is therefore held against independent movement in 15 the eyes 17 of the upper end of the bucket, while the head 21 and the plate 23, fitting in the channels of the eyes 12, constitute holding means which prevent the longitudinal displacement of the pin. The lower eyes 14 20 have openings considerably larger than those through the upper eyes and are, furthermore, provided with longitudinally-disposed grooves 26 that extend into the walls of the eyes in a plane that is transverse to the longitudinal axis of the element. Bushings in 25 the form of sleeves 27 fit in the eyes and have keys 28, that engage in the slots 26, whereby sleeves are held against rotation. The interior diameter of these sleeves is the same as 30 the openings through the eyes 17.

In assembling the buckets the upper eyes 17 of each are placed in coaxing relation with the bottom eyes 14^a of the adjacent link, and a pivot-pin 20 is passed through said alined eyes 35 and locked. The buckets and links will therefore be pivotally connected at a plurality of points, including an intermediate one, which greatly strengthens the connection and permits of the widening of the buckets. The 40 frictional bearing due to the swinging movements of the buckets will be between the pivot-pin and the bushings 27; but the wear thereon will be upon one side only, as all are held against relative movement in the elements to which they are secured. When 45 they become worn to a degree sufficient to loosen the joints and throw the buckets out of alinement, it is only necessary to unlock the pin and either turn it half-way around or 50 remove it entirely and insert it from the other end. In either case a new wearing-surface will be presented, while the old one will be moved to an inoperative position. In like manner the bushings may be interchanged 55 or reversed, so that the joints will be tightened and the bearings again alined. By this construction it will therefore be seen that a greatly-improved joint is provided which is not only stronger, but is more durable and 60 can be used for a longer time than those ordinarily constructed.

From the foregoing it is thought that the construction, operation, and many advantages of the herein-described invention will 65 be apparent to those skilled in the art without further description, and it will be understood that various changes in the size, shape,

proportion, and minor details of construction may be resorted to without departing from the spirit or sacrificing any of the advantages of the invention. 70

Having thus described my invention, what I claim as new, and desire to secure by Letters Patent, is—

1. In a bucket conveyer of the class described, the combination with the conveyer elements having pivotally-associated eyes, the outer face of one of the outer eyes being provided with a depressed seat, of a pin passing through the eyes, and a locking device 80 for the pin secured in the seat and detachably engaging the pin to hold it against longitudinal displacement. 75

2. In a bucket conveyer of the class described, the combination with the conveyer elements having pivotally-associated eyes, the outer face of one of the outer eyes being provided with a depressed seat, of a pin passing through the eyes and having a socket 90 that is located in the seat, and a locking device for the pin secured in the seat and detachably engaging in the socket of the pin to hold said pin against longitudinal displacement. 85

3. In a bucket conveyer of the class described, the combination with the conveyer elements having pivotally-associated eyes, the outer face of one of the outer eyes being provided with a depressed channel that intersects the opening through said eye, of a pin passing through the eyes and having an annular groove that is located in the channel, and a locking device secured in the channel and embracing the pin, being engaged in the groove thereof to hold said pin against longitudinal displacement. 95 100

4. In a bucket conveyer of the class described, the combination with conveyer elements having pivotally-associated eyes, the outer eyes of said elements being provided in 110 their outer faces with depressed seats, of a pin passing through the eyes of the elements, and holding means for preventing the longitudinal displacement of the pin, said means being located in the seats of both of the outer 115 eyes. 110

5. In a bucket conveyer of the class described, the combination with the conveyer elements having pivotally-associated eyes, the outer faces of both of the outer eyes being provided with channels, and a pivot-pin passed through the eyes and having a head that fits in the channel of one of the outer eyes, said pin being reversible so that the head can be fitted into the channel of the 125 outer eye to present a new wearing-surface to the eyes of the adjacent element. 120

6. In a bucket conveyer of the class described, the combination with the conveyer elements having pivotally-associated eyes 130 provided with alined openings therethrough, the outer faces of both of the outer eyes being provided with channels that intersect said openings, and a pivot-pin passing through

the eyes and having a head that projects on opposite sides of the pin and fits in the channel of one of the outer eyes, said pin being reversible so that the head can be fitted into 5 the channel of the other outer eye to present a new wearing-surface to the eyes of the adjacent element.

7. In a bucket conveyer of the class described, the combination with the conveyer 10 elements having pivotally-associated eyes, the outer faces of both of the outer eyes being provided with channels, and a pivot-pin passing through the eyes and having a head that fits in the channel of one of the outer 15 eyes, and locking means located in the channel of the other outer eye and engaging the pin to hold it against displacement.

8. In a bucket conveyer of the class described, the combination with the conveyer

elements having pivotally-associated eyes 20 provided with alined openings therethrough, the outer faces of both of the outer eyes being provided with similarly-shaped channels that intersect said openings, and a pivot-pin passing through the eyes and having a head 25 that projects upon opposite sides of the pin and fits in the channel of one of the outer eyes, and a locking-plate secured in the other channel and engaging the end of the pin opposite the head to hold said pin in place. 30

In testimony that I claim the foregoing as my own I have hereto affixed my signature in the presence of two witnesses.

ROBERT W. CHRISTIAN.
